(57) **CLAIM**

The ornamental design for a roller skate toe stop, as shown and described.

DESCRIPTION

FIG. 1 is a rear perspective view of a roller skate toe stop showing my new design in a use configuration with environment.

FIG. 2 is a front perspective view of the roller skate toe stop.

FIG. 3 is a front elevational view of the roller skate toe stop.

FIG. 4 is a rear elevational view of the roller skate toe stop.

FIG. 5 is a right side elevational view of the roller skate toe stop.

FIG. 6 is a left side elevational view of the roller skate toe stop.

FIG. 7 is a top view of the roller skate toe stop; and,

FIG. 8 is a bottom view of the roller skate toe stop.

The broken lines in FIG. 1 depict the environment of a roller skate that forms no part of the claimed design. The broken lines in FIGS. 1, 2, 4, 5, 6, 7 and 8 depict threading portions of the roller skate toe stop that form no part of the claimed design.
